UNITED STATES PATENT OFFICE.

ROBERT C. MATHES, OF NEW YORK, N. Y., ASSIGNOR TO WESTERN ELECTRIC COMPANY,
INCORPORATED, OF NEW YORK, N. Y., A CORPORATION OF NEW YORK.

TRANSMISSION CIRCUITS.

Application filed November 21, 1919. Serial No. 339,740.

To all whom it may concern:

Be it known that I, ROBERT C. MATHES, a citizen of the United States, residing at New York, in the county of Bronx, State 5 of New York, have invented certain new and useful Improvements in Transmission Circuits, of which the following is a full, clear, concise, and exact description.

This invention relates to transmission circuits and more particularly it relates to two-way repeating systems.

As is well known in the art, it is frequently found desirable to provide a repeating or amplifying system between two transmission lines. In one form such a repeating system may have, the transmission lines are terminated in a Wheatstone bridge type of circuit for securing two-way transmission from unidirectional amplifying systems. As is well known, the conjugate condition of such bridge circuits is maintained by providing networks which closely simulate the impedance of the transmission line, or by balancing two similar transmission lines against each other. It is further well known in the art that if a high degree of conjugacy is not obtained there is a critical amount of amplification beyond which one cannot go without setting up a local circulation of energy in the form of a sustained tone, commonly known as singing. It is evident, therefore, that if any condition exists other than the unbalance between line and network which causes the transmission 35 of electrical energy between the two circuits designed to be conjugate, such a condition will further limit the amount of gain which can be obtained from the set.

It has been found in practical arrangements of telephone repeater equipment that the capacities between the primary and secondary windings of the transformers employed afford a path for the transmission of energy between the parts of the circuit 45 presumably conjugate. As the transmission of such undesired potentials is through a series capacity, it is most efficient at high frequencies so that it may even result in a sustained singing at an inaudible frequency. This result, while not interfering as direct tone, seriously impairs the normal telephone transmission through the circuit and so necessitates a reduction in amplification.

In accordance with this invention, this objectionable loss in transmission efficiency

of a two-way repeater circuit may be overcome by shunting these undesired potentials through a low impedance path to ground. One way this may be accomplished is by grounding one or more neutral points of 60 the repeater system.

This invention will be better understood by reference to the following detailed description, taken in connection with the drawings in which Fig. 1 represents this invention embodied in a two-way 2-repeater system and Fig. 2 represents this invention embodied in a two-way one-repeater system.

Referring to Fig. 1 of the drawing 3, 3 and 4, 4 are two transmission lines between 70 which is located a two-way repeating system. Line 3, 3 terminates in a bridged circuit containing a balancing network 5 of such a character as to simulate the impedance of the line. Between line 3, 3 and 75 network 5 are inserted the four equal windings 6, 7, 8 and 9 of a repeating coil 10. Incoming currents from line 3 by a circuit connected between the coils 6 and 7 and coils 8 and 9 are impressed through a filter 11 80 upon an amplifier 12. The amplified currents in the output circuit of amplifier 12 are impressed upon outgoing line 4 by repeating coil 13 in a manner now well known to the art without any appreciable part 85 being directed back to the input of repeater 19. Similarly incoming currents from line 4 are impressed by connections taken between windings 14 and 15, and 16 and 17 through a filter 18 upon an amplifier 19. 90 The amplified currents of repeater 19 are impressed upon outgoing line 3. The balancing networks 5 and 20 for lines 3, 3 and 4, 4 respectively may be of any suitable design, for example they may be of the form 95 disclosed in the Hoyt Patent #1,167,694 of August 7, 1915. The preferred form of filters 11 and 18 is disclosed in the Campbell Patent #1,227,113 of May 22, 1917.

As pointed out above, a local circulation of power in the two halves of the repeater circuit other than that due to improper line balance is liable to occur, due for example to capacities between the windings of the 105 transformers in the circuit. For example, if the control electrode 21 of amplifier 12 were to undergo a change in potential, this change would be amplified by amplifier 12 so that the winding 22 of 110

repeating coil 13 would acquire a certain potential to ground. Due to the capacity present between winding 22 and the other windings of repeating coil 13, all the apparatus between repeating coil 13 and the primary of transformer 25 would therefore acquire a certain potential with respect to ground. The potential with respect to ground which the primary of transformer 25 thus has will be transmitted through the capacity between the primary and secondary windings of this transformer so as to impress a potential on the control electrode of amplifier 19. This amplified potential, due to the capacity effect between the primary winding and the secondary windings of transformer 10, will give all the apparatus located between the secondary of transformer 10 and the primary of transformer 24 a potential with respect to ground. This potential in turn will be transmitted through the capacities of transformer 24 to give a potential to the control electrode of amplifier 12 which potential will again be amplified by amplifier 12. It is evident that if the returned impulse is equal to the initial impulse, sustained singing will be set up. Even if an insufficient amount is fed back in this way to produce singing, its effect may add to unbalanced conditions otherwise present and so further limit the gain which may be obtained from the set. This effect might be called an "effective internal unbalance".

It is to be noted that each repeater, the secondary of each input transformer, and the primary of each output transformer are asymmetrically connected to ground, due to the grounded connections of the cathodes of the repeaters. The secondary of each output transformer, however, together with the filter and the primary winding of each input transformer are symmetrically located with respect to ground. That is, the potential to ground impressed upon the secondary of each output transformer does not create a current which flows serially through the two side conductors, but the effect is transmitted through the side conductors in parallel to the primary of each input transformer. In other words, the potential gives rise to longitudinal currents in this part of the circuit. This manner of the transfer of the potential to ground from the output transformer to the input transformer is therefore such that the high frequency singing set up thereby cannot be prevented by adjusting the constants of filter 11 and 18 to cut out the high frequency singing. These filters can be made to cut out high frequencies only when the currents of the undesired frequencies flow serially through the two side conductors of the circuit.

One way in which this local circulation of power may be overcome is to ground one or more neutral or central points in corresponding parts of the apparatus in that part of the repeater circuit which is symmetrically located with respect to ground. Thus these midpoints of the primary windings of input transformers 24 and 25 may be connected through a low impedance path to ground. With such a connection, potentials to ground which, for example, winding 22 may acquire, will give a potential to ground to the primary winding of transformer 25 due to the capacity between the primary and secondary windings of repeating coil 13, but when the midpoint of primary winding of transformer 25 is connected to ground, this potential finds a low impedance path to ground through this grounded connection.

Similarly if any potential in the unidirectional path containing repeater 19 is fed back through the capacity between the windings of repeating coil 10 to the other unidirectional path, this potential will find a ready path to the ground through the grounded connection of the midpoint of the primary winding of transformer 24. The provision of these two grounded points, therefore, eliminates transmission of energy from one half of the repeater circuit to the other through the capacities in the coil windings. In order that this undesired transmission may be eliminated most completely, it is desirable that the grounded connection should be at the central point of the primary windings of the transformers. If the grounded connection is not taken at substantially the midpoints of the winding, one of the two sides of each path would acquire a higher potential to ground than the other side, thereby creating an unbalanced condition which would allow the local circulation of power which it is desired to eliminate. Furthermore an unbalanced ground would unbalance the telephone circuits to which a repeater might be connected without intervening transformers.

Another way the local circulation of power may be overcome is by connecting the midpoints of the gain adjusting potentiometers 27 and 28 through a low impedance path to ground. If desired, this grounded connection may be taken through large condensers 29 and 30. This local circulation of power may be also prevented by connecting between the bridged points of the two repeating coils 10 and 13, two retardation coils 34 and 35 and by grounding the midpoints of these two coils. Any potential to ground that the secondary of repeating coil 13 would acquire due to the potential to ground in the primary of the repeating coil would be prevented from reaching amplifier 19 since the energy would find a ready path to ground through the grounded connection of the midpoint of

retardation coil 34. Still another way of accomplishing the desired result is to ground the midpoints of windings of the phantom coils 36, 37, 38, and 39.

5 As shown in the drawing, the gain adjusting potentiometer 28 preferably should have adjustable contacts 80 and 81 to both terminals of the primary winding of the input transformer 24. The use of double adjustable contacts allows the setting of the potentiometer to change without interfering with the symmetrical connection to ground of the leads from the midpoints of the three-winding transformer to the input transformer 24. If only one adjustable contact instead of two were employed, for example, to vary the repeater gain, any variation in its position would change the symmetrical connection to ground through condenser 30 of the terminals of the primary winding of transformer 24, in the case where the only grounded midpoints were the midpoints of the potentiometers.

Several ways have been described above 25 for increasing the transmission efficiency of the two-way repeater system for eliminating an "effective internal unbalance" by providing a symmetrical path to ground for that portion of the repeater apparatus which is 30 floating with respect to ground. In any particular case, it may be desirable to employ one of the above methods in preference to the others, or it may be found desirable to employ all the methods in the same circuit.

35 Fig. 2 illustrates this invention in connection with a two-way one repeater system in which balancing networks are eliminated and the one transmission line 50 is balanced by the other transmission line 51. Located 40 between the two lines 50 and 51 are the four windings 52, 53, 54 and 55 of repeating coil 56. Across the bridged points of these windings are connections which lead through a filter 57 and the gain adjusting potentiometer 45 58 to the primary winding of the input transformer 59. Amplifier 60 has its input terminals connected to the secondary of transformer 59 and has its output terminals connected to the primary winding of 50 repeating coil 56. With such an arrangement signals originating in either of the two transmission lines will be impressed through the filter upon the amplifier and the amplified signals will be impressed back on the 55 two transmission lines by repeating coil 56.

As in the repeating system of Fig. 1, the repeating system of Fig. 2 may be freed from any circulation of power, other than that due to line unbalance, by either grounding the 60 mid point of gain adjusting potentiometer 58 or mid point of the primary winding of the input transformer 59, or by grounding the midpoint of the retardation coil 63 which is connected across the bridge points.

35 From the above description it is apparent

that applicant's invention is not limited to the particular circuit arrangements above described and that it may be variously modified without departing in any way from the spirit of this invention as defined in the 70 appended claims.

What is claimed is:

1. A two-way repeating system comprising a uni-directional path comprising an 75 amplifier and impedance devices, a symmetrical connection to ground for certain of said devices, and an asymmetrical connection to ground for other of said devices.

2. A two-way repeating system comprising a uni-directional path containing a repeater asymmetrically connected to ground, 80 a transformer, apparatus in said path connected through said transformer to said repeater, and means for providing a symmetrical path to ground for said apparatus. 85

3. A two-way repeating system comprising a uni-directional path containing devices asymmetrically connected to ground, 90 devices symmetrically connected to ground, and a transformer between said devices. 95

4. A two-way repeating system comprising a uni-directional path formed of two line conductors and containing a repeater, 100 an impedance symmetrically located with respect to said line conductors and to the input terminals of said repeater, and a connection to ground from the midpoint of said impedance for preventing output energy from said repeater from being fed back upon the input terminals of said repeater. 105

5. In an electric system, a two-way repeating circuit comprising a repeater in each of two unidirectional paths, an output transformer for one of said repeaters and means for preventing energy from the primary of 110 said transformer from being fed back to the input of said last mentioned repeater, said means comprising a grounded device symmetrically located with respect to the two line conductors forming the electrical path between said transformer and said last mentioned repeater. 115

6. A two-way repeating system comprising a repeater in each of two unidirectional paths, an output transformer for one of 120 said repeaters, and means for preventing energy from the primary of said transformer from being fed back to the input of said last mentioned repeater, said means comprising a shunt to ground equally effective for both of the two line conductors forming the electrical path between said transformer and said last mentioned repeater. 125

7. A two-way repeating system comprising a repeater in each of two unidirectional paths, an output transformer for one of said repeaters and means for preventing energy from the primary of said transformer from being fed back to the input of said last men- 130

- tioned repeater, said means comprising an impedance connected in shunt between the two line conductors forming the electrical path between said transformer and said last 5 mentioned repeater, said impedance having its midpoint connected to ground.
8. A two-way repeating system comprising a repeater in each unidirectional path, an output transformer for one of said repeaters and means for preventing energy from the primary of said transformer from being fed back to the input of said last mentioned repeater, said means comprising an impedance of negligible capacity reactance 10 connected in shunt between the two line conductors forming the electrical path between said transformer and said last mentioned repeater, said impedance having its midpoint connected to ground.
- 15 20 9. A two-way repeating system comprising a unidirectional path for repeating in one direction, a second unidirectional path for repeating in the opposite direction, a repeater in each of said paths, and means for preventing energy from one of said paths from being fed back over the other of said paths to the repeater in said first mentioned path, said means comprising an impedance connected across the two line conductors forming the conducting path in said 25 system, said impedance having its midpoint grounded, said grounded connection being equally effective for potentials in either of the line conductors.
- 30 35 10. A two-way repeating system comprising a unidirectional path for repeating in one direction and a second unidirectional path for repeating in the opposite direction, a repeater in each of said paths and an impedance connected effectively in shunt to the 40 input terminals of each of said repeaters and having their midpoints connected to ground for preventing output energy from one of said repeaters from being impressed upon the 45 input terminals of the other of said repeaters.
11. On an electric system two transmission lines, a two-way repeating circuit between said lines, said circuit comprising a balancing network for each of said lines, 50 a unidirectional path for repeating in one direction between said lines, a second unidirectional path for repeating in the opposite direction between said lines, and an impedance connected effectively across the 55 bridge points connecting one of said lines with its balancing network, said impedance having its midpoint connected to ground.
12. In combination, two line sections, an 60 artificial line for balancing each of said line sections, a uni-directional path for repeating in one direction between said line sections, a second uni-directional path for repeating in the opposite direction, a repeater located in each of said paths and having input and 65 output terminals, an impedance, and means comprising a connection to ground from the midpoint of said impedance for preventing the local circulation of power in said paths.
13. In combination, two line sections, an 70 artificial line for balancing each of said line sections, a uni-directional path for repeating in one direction between said line sections, a second uni-directional path for repeating in the opposite direction, a repeater located in each of said paths and having input and output terminals, an impedance, and means for preventing longitudinal currents in said paths from causing said repeaters to sing.
14. A two-way repeating system comprising 75 a uni-directional path containing a repeater, a wave filter for suppressing certain frequencies of currents flowing serially in said path, and means for suppressing longitudinal currents in said path of corresponding frequencies.
15. In combination, an incoming line, a 80 uni-directional path associated with said line and comprising a vacuum tube amplifier, a wave filter in said path for suppressing certain frequencies of currents flowing serially in said path, and means between said line and said amplifier for preventing longitudinal currents from being impressed upon said amplifier.
16. In combination, an incoming line, a 85 uni-directional path associated with said line and comprising means for suppressing certain frequencies when they consist of currents flowing serially in said path, and means for suppressing certain frequencies in said 90 path when they consist of longitudinal currents in said path.
17. A two-way repeating system comprising a uni-directional path containing a repeater, a wave filter for preventing currents flowing serially in said path from causing said repeater to sing, and means for preventing longitudinal currents in said path from causing said repeater to sing.
18. A repeating system comprising a 95 Wheatstone bridge network having four impedance arms, repeater input terminals, repeater output terminals, a connection from the midpoint of the first and the second arms of said bridge to one of said repeater input 100 terminals, a connection from the midpoint of the third and fourth arms to another of said repeater input terminals, a connection from the midpoint of said first and fourth arms to a repeater output terminal, a connection from the midpoint of the second and third arms to a second repeater output terminal, and a symmetrical path to ground 105 for said first two connections for preventing output energy from said output terminals from being impressed upon said input terminals.
19. A repeating system comprising a 110 Wheatstone bridge network having four impedance arms, repeater input terminals, re- 115
- 120
- 125
- 130

repeater output terminals, a connection from the midpoint of the first and the second arms of said bridge to one of said repeater input terminals, a connection from the midpoint of 5 the third and fourth arms to another of said repeater input terminals, a connection from the midpoint of said first and fourth arms to a repeater output terminal, a connection from the midpoint of the second and third arms 10 to a second repeater output terminal, an impedance effectively in shunt to said first two connections, and a connection to ground from the midpoint of said impedance for preventing the local circulation of power 15 between said output terminals and said input terminals.

20. A repeating system comprising a Wheatstone bridge network having four impedance arms, repeater input terminals, repeater output terminals, a connection from the midpoint of the first and the second arms of said bridge to one of said repeater input terminals, a connection from the midpoint of the third and fourth arms to another of 25 said repeater input terminals, a connection from the midpoint of said first and fourth arms to a repeater output terminal, a connection from the midpoint of the second and third arms to a second repeater output terminal, and means for preventing potentials 30 said first two connections may have to ground due to currents in parallel in said connections from being impressed upon said repeater input terminals.

35. 21. A repeating system comprising a uni-directional path containing an amplifier, a gain adjusting potentiometer for said amplifier, connections from the input terminals of said amplifier symmetrically and adjustably 40 connected to points on said potentiometer, and means for preventing longitudinal currents in said path from causing said amplifier to sing.

45. 22. A repeating system comprising a uni-directional path containing an amplifier, a gain adjusting potentiometer for said amplifier, connections from the input terminals of said amplifier symmetrically and adjustably connected to points on said potentiometer, 50 and a connection to ground from the midpoint of said potentiometer.

23. A repeating system comprising a uni-directional path containing an amplifier, a gain adjusting potentiometer for said amplifier, connections from the input terminals 55 of said amplifier symmetrically and adjustably connected to points on said potentiometer, and a symmetrical path to ground for a portion of said connections for preventing said amplifier from singing. 60

24. In combination, two line sections, a uni-directional path between said lines comprising a repeater having input and output terminals, a transformer between one of said lines and said input terminals, a gain adjusting potentiometer, connections from the terminals of the primary winding of said transformer symmetrically and adjustably connected to points on said potentiometer, and a path to ground for said connections. 70

25. In combination, two line sections, a uni-directional path between said lines comprising a repeater having input and output terminals, a transformer between one of said lines and said input terminals, a gain adjusting potentiometer, connections from the terminals of the primary winding of said transformer symmetrically and adjustably connected to points on said potentiometer, and means for preventing longitudinal currents in said path from causing said repeater 80 to sing.

26. In combination, two line sections, an artificial line for balancing each of said sections, a uni-directional path for repeating in 85 one direction between said line sections, a second uni-directional path for repeating in the opposite direction, a repeater in each of said paths, a wave filter in each of said paths for preventing said repeaters from 90 singing due to series currents in one of said paths produced by potentials in the other of said paths, and means for preventing said repeaters from singing at a high frequency due to longitudinal currents in one 95 of said paths produced by potentials from the other of said paths.

In witness whereof, I hereunto subscribe my name this 19th day of November, A. D., 1919.

ROBERT C. MATHEWS.
